Attest.

United States Patent Office.

M. E. BURTLESS, OF SENECA FALLS, NEW YORK.

Letters Patent No. 90,495, dated May 25, 1869.

IMPROVEMENT IN DITCHING-MACHINES.

The Schedule referred to in these Letters Patent and making part of the same.

To all whom it may concern:

Be it known that I, M. E. BURTLESS, of Seneca Falls, in the county of Seneca, and State of New York, have invented a certain new and useful Improvement in Ditching-Machines; and I do hereby declare that the following is a full and exact description thereof, reference being had to the accompanying drawings, making part of this specification, in which—

Figure 1 is a side elevation.

Figure 2, a plan.

Figure 3, a cross-section.

Like letters of reference indicate corresponding parts in all the figures.

My invention consists in the special construction and arrangement of the machine, as hereinafter set forth.

In the drawings—

A indicates the frame, which is composed of two parallel iron bars *a a*, bolted and braced together by cross-pieces *b b*, at the front and rear, as shown.

The front end of the frame is provided with a long clevis bar, B, stayed firmly by braces *c c*, and having a series of holes, *d d*, for the attachment of the draught-pole or chain.

As the machine cuts deeper into the ditch, the draught is changed higher and higher in the holes *d d*, so as to draw uniformly upon the machine.

The machine is supported by two wheels, C C'.

The front one is connected with a curved bearing, D, whose shank, *f*, is swivelled in bearing *b*, so as to turn freely, at the same time that it has a free up-and-down sliding movement in its socket.

On the head of this shank rests the end of a screw, E, resting in bearing *e*, and operated by means of an ordinary hand-wheel, *g*.

By this arrangement the wheel is at liberty to turn in any direction to follow the draught, keeping in place by the curved bearing D, and at the same time it is also capable of regulating the depth and grading the ditch by the turning of the screw as the machine cuts deeper into the ditch.

The hind wheel is simply shown as attached to a fixed bearing, D', but I design, in some cases, to make it adjustable by a screw, in the same manner as the front one. It may be used either way, as necessity may require.

To the rear of the machine is attached an inclined scoop, G, having a point, *h*, which cuts and opens the way in the ditch.

The lower end is connected with the frame by a brace, H, which sustains it firmly in place.

In front of the scoop are two coulters, I I, one standing a little in front of the other, and at such a distance

apart as to correspond with the width of the ditch to be cut.

These coulters cut the sides of the ditch, while the scoop scrapes up and elevates the dirt.

To insure strength, I prefer to make the scoop of three parts, *i k k*, which are at right angles to each other, as shown.

A mould-board, K, is made to adjust higher or lower upon the scoop, by means of screw-hooks *l l*, on opposite sides, which catch under the edges of side-pieces *k k*, and are tightened by nuts *m m*.

This arrangement enables the mould-board to be adjusted higher as the machine cuts deeper, and thus always stand upon a level with the surface of the ground, so as to throw out the dirt that rises on the scoop.

This mould-board may be either single, as shown, to throw the dirt all on one side, or double, to throw it on both sides.

It is provided, preferably, with a wing or wings, *n*, which slants a little upward beyond the level of the mould-board itself, to throw the dirt further out as the amount grows large on the bank.

At a suitable position on the frame is a vertical loop, L, having a series of holes, *p p*, in any of which fits a handle, *q*, that projects laterally, and enables an attendant to support the machine in an upright position as it passes over the ditch.

This handle can be adjusted higher as the machine cuts deeper.

An adjusting-platform, P, and a seat, Q, are employed for the operator of the hand-wheel *g*, who is also the driver.

The arrangement of the parts as above described, enables the machine, as it passes successively back and forth, to be adjusted deeper and deeper, to cut the ditch of the desired depth.

This arrangement of parts I believe to be original with myself.

What I claim as my invention, and desire to secure by Letters Patent, is—

A ditching-machine, composed of the frame A, clevis-bar B, adjusting-wheels C, with bearings D, screw E, scoop G, coulters I I, and adjustable mould-board K, the whole arranged as described, and operating in the manner and for the purpose specified.

In witness whereof, I have hereunto signed my name, in the presence of two subscribing witnesses.

M. E. BURTLESS.
